UNITED STATES PATENT OFFICE.

WRIGHT RHODES, OF MANCHESTER, ENGLAND.

CUTTING IMPLEMENT.

1,360,797.

Specification of Letters Patent. Patented Nov. 30, 1920.

Application filed February 1, 1916. Serial No. 75,479.

To all whom it may concern:

Be it known that I, WRIGHT RHODES, a subject of the King of Great Britain and Ireland, residing at Tower Chambers, Spring 60
Gardens, Manchester, in the county of Lancaster, England, have invented new and useful Improvements in Cutting Implements, of which the following is a specification.

This invention relates to a device or appliance for stripping or removing "waste" from roving and like tubes and bobbins.

An exhausted roving tube or bobbin always contains a certain amount of waste roving which is stripped or removed before 15 the tube or bobbin is used again. When the tube or bobbin is new the waste can generally be screwed or twisted off by hand, but if the surface of the tube or bobbin is not perfectly smooth it is often difficult to screw 20 or twist off the waste and in such cases it is not unusual for the operative to cut off the waste by drawing the blade of a knife lengthwise along the tube or bobbin. Such cutting off of the waste, however, frequently leads 25 to the cutting and consequent damaging of the tube or bobbin and the object of the present invention is to provide a device or appliance whereby waste which cannot be readily removed by screwing or twisting it off can 30 be cut off without any possibility of cutting and damaging the tube or bobbin.

A device or appliance in accordance with the invention comprises essentially a holder or carrier provided with or having mounted 35 or arranged on it a prong-like member adapted to be inserted between the tube or bobbin and the waste thereon and adapted to raise the latter clear of the tube or bobbin, and a cutter adapted to sever the waste when 40 it is raised.

In the accompanying drawings Figure 1 is a side elevation, Fig. 2 a front view, and Fig. 3 a perspective view of the preferred form of device or appliance in accordance 45 with my invention, and Fig. 4 is a perspective view of the components of the device or appliance detached or separated.

Referring to the drawings the preferred form of device or appliance in accordance 50 with my invention comprises a steel or other suitable holder *a* provided with a head *a*¹ in which is fashioned a groove *a*². At the front of the holder *a* is mounted a depending prong *b* the upper end or shank *b*¹ of which 55 is bent at right angles and clamped by a

clamping plate *b*² and screw *b*³ in the groove *a*² in the top of the holder. The upper end *b*¹ of the prong *b* is provided with a slot *b*⁴ (Fig. 4) in order to render the prong adjustable as to position in front of the holder *a*. The prong *b* may, however, be clamped to the holder *a* and be adjustable in any other suitable way. The depending part of the prong is provided with a comparatively long and narrow slot *b*⁵ and tapers both in thickness and width to its lower end. The prong is also provided with guide wings *b*⁶ to assist in maintaining it in position against the tube or bobbin in operation and its front surface is preferably concaved to enable it to 70 better seat against the tube or bobbin.

To the side of the holder *a* is clamped a cutter *c* which consists of a double-edged wafer blade. The cutter is positioned on studs *a*³ on the side of the holder so that its front cutting edge is inclined and at the top projects beyond the front of the holder and into, but not through, the slot *b*⁵ in the prong *b*. The cutter *c* is clamped and the necessary rigidity imparted to the projecting part 80 of its operative cutting edge by a clamping plate *d* also positioned on said studs *a*³ and secured by a screw *d*¹.

In use the prong *b* is inserted between the tube or bobbin and the waste thereon and the device or appliance then drawn smartly lengthwise of the tube or bobbin. As the device or appliance is drawn along the prong *b* raises the coils or turns of the waste from the surface of the tube or bobbin which 90 are tightened or tensioned as they pass on the upper and larger part of the prong where they are severed by the cutter *c*.

Although I prefer a double-edged cutter as aforesaid which can be changed or adjusted to bring either end of either cutting edge into operation when the other or others is or are dulled, I may employ a single-edged or any other suitable cutter.

As will be obvious, my improved device 100 or appliance may be considerably modified without departing from the nature or spirit of my invention. For example, I may arrange the prong and cutter so that when the device or appliance is in use either it or the 105 tube or bobbin is also turned and the waste is stripped or cut spirally. Further I may mount the cutter on or form it integral with the prong and so arrange it that its cutting, or operative cutting, edge or edges is or are 110

at right angles to or at either or both sides of the prong.

It will, of course, be understood that my improved device or appliance is applicable for use only with tubes or bobbins that are not provided with annular or circumferential grooves.

What I claim as my invention and desire to secure by Letters Patent is:—

- 10 1. A cutting implement of the class described comprising a holder member, a prong-like member projecting from the holder member and having its free end portion disposed adjacent to one side of the latter in fixed angular relation thereto, means by which the said prong-like member may be adjusted relative to the said holder member side without changing the angular relation of the same, and a cutting blade secured fixedly to one of the said members and disposed so that it bridges the gap between members and has its sharp edge at an oblique angle to one of the latter.
- 20 2. A cutting implement of the class described comprising a holder member, a prong-like member projecting from the holder member and having a pointed free end portion disposed adjacent to one side of the latter in fixed angular relation thereto, one of said members having a longitudinal slot therein, and a cutting blade carried by the other member and disposed so that it extends across the gap between members and into

the said slot with its sharp edge facing the end of the prong-like member.

3. A cutting implement of the class described comprising a holder having a groove formed in one edge thereof, a prong-like member having a slot formed therein, an angular extension formed on said prong-like member and mounted within said groove, means for securing said extension in adjusted position within said groove, to adjust said prong-like member to or away from one edge of said holder, and a cutting member carried by said holder and having a portion thereof extending into said slot.

4. A cutting implement of the class described comprising a holder, a prong-like member disposed contiguous to the holder, a plurality of studs projecting from the holder, a wafer-like cutting blade projecting into said prong-like member and having a plurality of holes adapted to register with the studs on the holder and receive the same, a clamping plate removably mounted on the holder and having holes adapted to register with and receive the said studs, and means for securing the said plate to the holder.

In testimony whereof I have signed my name to this specification in the presence of two subscribing witnesses.

WRIGHT RHODES.
